[57] CLAIM

The ornamental design for a hot pad, as shown.

DESCRIPTION

FIG. 1 is a top, front and right side perspective view of a hot pad showing my new design;

FIG. 2 is a top plan view thereof;

FIG. 3 is a bottom plan view thereof;

FIG. 4 is a front elevational view thereof, the rear elevational view being a mirror image;

FIG. 5 is a left side elevational view thereof; and,

FIG. 6 is a right side elevational view thereof.

The broken lines in FIGS. 1-3 and 5-6 represent conventional stitching.

FIG. 1

FIG. 2

FIG. 3

FIG. 4

FIG. 5

FIG. 6
